(57) **CLAIM**

The ornamental design for kitchen faucet, as shown and described.

DESCRIPTION

FIG. 1 is a left side view of the kitchen faucet of my invention;

FIG. 2 is a right side view;

FIG. 3 is a front view;

FIG. 4 is a rear view;

FIG. 5 is a top view;

FIG. 6 is a bottom view; and,

FIG. 7 is a front perspective view.

The broken lines are included for the purpose of illustrating a portion of the kitchen faucet that forms no part of the claimed design.
